UNITED STATES PATENT OFFICE.

WILLIAM T. DURHAM, OF RIDGE SPRING, SOUTH CAROLINA.

SNAP-HOOK.

1,308,055.

Specification of Letters Patent.

Patented July 1, 1919.

Application filed April 2, 1918. Serial No. 226,274.

To all whom it may concern:

Be it known that I, WILLIAM T. DURHAM, a citizen of the United States, residing at Ridge Spring, in the county of Saluda and 5 State of South Carolina, have invented new and useful Improvements in Snap-Hooks, of which the following is a specification.

This invention relates to snap hooks, and particularly to snap hooks of that type 10 formed from a single piece of spring wire.

One object of the invention is to provide a construction giving maximum strength, simplicity and durability, and which produces a substantially flat and compact form 15 of snap hook.

Another object of the invention is to provide a construction which obviates the use 20 of spring coils or ties between the parts, and which affords increased strength and durability by disposing the hook and tongue in close proximity to the body of the snap hook.

A still further object of the invention is to provide a construction in which parts of 25 the body and bill coöperate to form a connecting loop, whereby a loop of increased strength is produced and spreading of the parts thereof prevented.

The invention consists of the features of 30 construction, combination and arrangement of parts, hereinafter fully described and claimed, reference being had to the accompanying drawing, in which:—

Figure 1 is a perspective view of a snap 35 hook constructed in accordance with my invention.

Fig. 2 is a side elevation of the snap hook.

Fig. 3 is a face or top plan view of the same.

40 In carrying my invention into practice I provide a snap hook having a body portion of substantially triangular form, provided at its narrow end with a backturned hook and at its wide end with a connecting or 45 strap receiving loop, together with a tongue arranged for coöperation with the hook, the body and tongue having complementary portions forming the said strap receiving or connecting loop, all of the parts being 50 formed from a properly bent piece of spring wire.

As shown, the wire of which the snap hook is composed is bent to provide a body 55 consisting of a pair of longitudinally extending main arms 1 and 2, which converge in a direction toward the hook end of the

snap hook. The converging ends of these arms 1 and 2 are arranged in close relationship and are connected by a doubled portion of the wire, said doubled portion of the wire 60 being formed to provide a substantially U-shaped hook 3. This hook 3 extends over the converging ends of the arms 1 and 2 in close relationship thereto and substantially parallel therewith, by which arrangement the 65 hook is made comparatively short and disposed so as to lie close to the main arms, thus avoiding objectionable spacing of the hook from the frame and securing greater compactness and increased strength and rigidity 70 of the hook.

The arm 1 is substantially straight throughout, and at the wide end of the frame is bent at right angles toward the arm 2 to provide a lower cross piece 4, thence 75 bent forwardly at right angles or toward the hook 3 to provide a short arm 5 lying beneath the adjacent or rear end of the arm 2, and thence rebent backward at right angles toward the arm 1 and across the 80 space between the arms 1 and 2 to provide an intermediate cross piece 6. This cross piece 6 is spaced from and arranged parallel with the lower rear cross piece 4 and co-operates with the rear end of the arm 2 and 85 an upper cross piece 7 bent laterally therefrom to form an oblong rectangular connecting or strap receiving loop 8.

The arm 1 is substantially straight or has its portions lying substantially in the 90 same plane throughout, but the intermediate portion of the arm 2 is bent upward at a slight angle, as shown at 9, above the plane of the plane of the intermediate portion of the arm 1, so as to dispose the rear end 10 95 of said arm 2 above the plane of the arm 1 so that it will overlie and rest upon the short arm 5 and coöperate therewith to form one side of the strap receiving loop 8. The cross piece 7 is bent at right angles to the 100 portion 10 of the arm 2 and extends over the lower cross piece 4 to form therewith the rear cross bar of the loop 8, the arrangement being also such that the loop forming portions of the arms 1 and 2 lie substantially 105 in parallel relation, thus rendering the snap hook substantially flat and of compact form at the loop end.

The parts 4, 5 and 6 are formed by one terminal of the wire extending from the 110 arm 1, and the other terminal of the wire extending from the free end of the cross

piece 7 projects forwardly from the loop 8 toward the hook 3 in the form of a spring tongue 11 which is arranged to bear at its free end against the underside of the bill of the hook. As shown, the tongue 11 extends inwardly at an angle from the inner end of the cross piece 7 toward the hook so as to lie at its free end centrally between the converging ends of the arms 1 and 2, the said free end of the tongue being provided with an inbent terminal 12 forming a latch or detent extending across the throat of the hook 3 to close the same when the hook is engaged with an object and prevent disconnection of the snap hook therefrom. This detent or latch 12 has its free end projecting downwardly into the space between the converging ends of the arms 1 and 2, and thus is adapted to serve as a stop to limit the lateral movement of the tongue 11 and prevent the tongue from being forced laterally outward to an inoperative position.

In practice, the snap hook is preferably formed from a single piece of round wire, galvanized, nickel-plated, japanned or otherwise treated to protect it from rust, and it will be understood that in practice the wire may be of any desired gage according to the size of the snap hook and the strength and rigidity which it is intended it to have.

In the use of the snap hook, the end of the strap or other harness member or part to which the hook is to be attached is passed through and connected with the loop 8, the snap hook then being employed in the usual manner to connect said strap or other part with an article to which it is to be coupled. It will be apparent from the foregoing description that the construction is such that the snap hook may be readily held in the hands and the tongue depressed by means of the thumb or pressure of the object to be engaged thereon, thus allowing the tongue to be readily forced open for the connection or disconnection of the object, while the closing of the throat of the hook by the detent 12 will secure absolute safety and prevent disconnection of the object from the hook until such object is intentionally released.

Important advantages arising from my construction are, among others, that the snap hook as a whole is made in a compact shape and comparatively flat form, thus enabling it to be conveniently packed in close compass, and also adapting it to lie snugly in contact with the parts to be coupled. Also it will be seen that the strap or part coupled to the loop 8 will be connected with doubled portions of the wires, giving increased secur-

ity of connection, and at the same time the strap will hold the complemental loop forming parts assembled and prevent their disconnection or displacement. By the construction described it will also be evident that the hook 3 is arranged to lie close to the body of the snap hook, thus increasing its strength and rigidity of connection, while at the same time giving compactness to this portion of the device. Furthermore, it will be seen that the use of ties for holding parts of the snap hook in relative position is avoided, thus simplifying the construction, and that the use of a spring coil is also obviated, thus reducing the size of the snap hook and avoiding the bunglesome appearance incident to the use of ordinary wire snap hooks provided with coils. The simplicity of construction of my improved snap hook also adapts it to be manufactured and sold at a comparatively low cost.

Having thus fully described my invention, I claim:—

1. A bent wire hook consisting of a loop, of which the side members extend divergently from the hook bill to form a shank, of which the sides are rebent in opposite directions and in parallel planes to form respectively an attaching eye and a hook closing terminal, of which the latter extends unobstructedly from the outer side of said eye to the hook and terminates in a throat closing element disposed perpendicularly to the plane of said divergent side members. 85

2. A snap hook formed of a single strand of wire bent upon itself at an intermediate point to provide a pair of arms diverging from the bending point, the portions of said arms near the point of bending being curved in the general direction of the arms and forming a bill, the said strand near the end of one of said arms being bent transversely, rearwardly and inwardly to provide a loop of substantially rectangular shape and offset from the arm of which it is a part, the other arm extending over and lying upon the said backwardly bent portion and then being bent so as to overlie the said transversely bent portion, the remainder of the said arm being then bent so as to provide a spring tongue overlying a part of the first mentioned arm and having its end disposed within and against the bill, and the extremity of said tongue being bent at substantially right angles to the body thereof and disposed between the divergent ends of the arms and closing the end of the bill. 100 105 110 115

In testimony whereof I affix my signature.

WILLIAM T. DURHAM.
